CLAIM

The ornamental design for hose hanger front plate, as shown and described.

DESCRIPTION

FIG. 1 is a top front right perspective view of the hose hanger front plate of the present invention;

FIG. 2 is a top rear left view thereof;

FIG. 3 is a front view thereof;

FIG. 4 is a right side view thereof;

FIG. 5 is a left side view thereof;

FIG. 6 is a top view thereof; and,

FIG. 7 is a bottom view thereof.

The portions of the hose hanger front plate illustrated in broken lines are not claimed.
